Primary Examiner — Darlington Ly(57) **CLAIM**

The ornamental design for an automotive radiator grille, as shown and described.

DESCRIPTION

FIG. 1 is a front elevation view of an automotive radiator grille showing my new design;

FIG. 2 is a top plan view thereof;

FIG. 3 is a bottom plan view thereof;

FIG. 4 is a right side elevation view thereof;

FIG. 5 is a left side elevation view thereof;

FIG. 6 is a bottom, front, and right side perspective view thereof;

FIG. 7 is a top, front, and left side perspective view thereof; and,

FIG. 8 is a cross-sectional view thereof, where the cut plane is taken along line 8-8 indicated in FIG. 1.

The broken line showing of the rear surface configuration or portions of the automotive radiator grille do not form part of the claimed design.

1 Claim, 8 Drawing Sheets8
